UNITED STATES PATENT OFFICE.

JOHN Y. KING, OF LANSDOWNE, PENNSYLVANIA.

DESIGN FOR AN AIR-FEEDING DEVICE FOR STOVES AND OTHER COAL-BURNING APPLIANCES.

60,149.

Specification for Design.

Patented Jan. 3, 1922.

Application filed September 15, 1920. Serial No. 410,569. Term of patent 14 years.

To all whom it may concern:

Be it known that I, JOHN Y. KING, a citizen of the United States, residing at Lansdowne, in the county of Delaware and State of Pennsylvania, have invented a new, original, and ornamental Design for Air-Feeding Devices for Stoves and other Coal-Burning Appliances, of which the following is a specification, reference being had to the accompanying drawing.

Figure 1, is a perspective of the device embodying my design.

Figure 2, is a side elevation thereof.

My design primarily consists of an air

feeding device having two faces formed upon the periphery thereof, said faces standing at an angle to each other, each of said faces being made up of facets to give to the exterior of said barrel the general appearance of a cut diamond.

What I claim is—

The ornamental design for an air feeding device for stoves and other coal burning appliances, as shown.

JOHN Y. KING.

Witness:

S. S. WILLIAMSON.
